(57) **CLAIM**

The ornamental design for a puck light fixture, as shown and described.

DESCRIPTION

FIG. 1 is a perspective view of my new design for a light fixture with phantom lines indicating an array of stand-offs, or studs, along with apertured mounting brackets and various wall thicknesses throughout the figures, which form no part of the claimed design;

FIG. 2 is a bottom plan, or front view of the fixture of FIG. 1;

FIG. 3 is a top plan, or back view of the fixture of FIG. 1;

FIG. 4 is a side elevation of the fixture of FIG. 1; and,

FIG. 5 is a cross-section view taken along lines 5—5 in FIG. 2 showing the light array and reflector seen in FIGS. 1 and 2.
